US00D774537S

(12) **United States Design Patent** (10) Patent No.: **US D774,537 S**
Hong et al. (45) Date of Patent: **** Dec. 20, 2016**

(54) **DISPLAY SCREEN OR PORTION THEREOF WITH GRAPHICAL USER INTERFACE**

(71) Applicant: **Samsung Electronics Co., Ltd.**, Suwon-si, Gyeonggi-do (KR)

(72) Inventors: **Seongkook Hong**, Seoul (KR); **Jinwoo Choi**, Seoul (KR); **Cheolhoon Kang**, Seoul (KR)

(73) Assignee: **SAMSUNG ELECTRONICS CO., LTD.**, Gyeonggi-Do (KR)

(**) Term: **15 Years**

(21) Appl. No.: **29/553,783**

(22) Filed: **Feb. 4, 2016**

(30) **Foreign Application Priority Data**

Sep. 2, 2015 (KR) 30-2015-0044199

(51) **LOC (10) Cl.** **14-04**

(52) **U.S. Cl.**

USPC **D14/486**

(57) **CLAIM**

The ornamental design for a display screen or portion thereof with graphical user interface, as shown and described.

DESCRIPTION

The FIGURE is a front view of a display screen or portion thereof with graphical user interface, showing our new design.

The broken lines showing the display screen and portions of the graphical user interface are included for the purpose of illustrating environmental structure and form no part of the claimed design.

1 Claim, 1 Drawing Sheet
